UNITED STATES PATENT OFFICE.

DAVID P. WHITESELL, OF EL DORADO, OHIO.

ENGINE CROSS-HEAD.

SPECIFICATION forming part of Letters Patent No. 388,937, dated September 4, 1888.

Application filed October 13, 1887. Serial No. 252,241. (No model.)

To all whom it may concern:

Be it known that I, DAVID P. WHITESELL, a resident of El Dorado, in the county of Preble and State of Ohio, have invented certain new 5 and useful Improvements in Engine Cross-Heads, of which the following is a specification.

The object of my invention is, first, to overcome or avoid the dead-center of an engine crank 10 or the crank of other driving-motors; second, to employ mechanical devices, so that power is applied nearly uniformly to the crank-pin during the entire portion of its revolution, instead of having it progressively increase and 15 decrease upon either side of the dead-centers.

I have represented it as adapted to be used with the piston of an engine, but do not limit myself to this use of my mechanical device.

The various features of my invention are 20 illustrated in the accompanying drawings, making a part of this specification, in which—

Figure 1 is an elevation of my improvement attached to the piston-rod. Fig. 2 is an elevation of the reverse side of Fig. 1. Fig. 3 is 25 a vertical section of the cross-head, showing the section of the piston-rod in elevation. Fig. 4 is a section on line *y y*, Fig. 3. Fig. 5 is an elevation of the cross-head and cam. Fig. 6 is a section on line *x x*, Fig. 1. Fig. 7 is a 30 perspective view of the cam-guide. Fig. 8 is a top plan view of Fig. 2.

A B represent end pieces of the frame; C D, side frame-pieces which serve as ways upon which the cross-head moves.

35 E represents the piston-rod of an ordinary engine. This frame is suitably supported so that the piston-rod will move in a direct line with the axial plane of the cylinder, this frame serving as the ordinary cross-head guide or 40 support.

F represents the cross-head, which is constructed so as to serve as a support to the remaining operative parts of the driving devices. The center of this cross-head is pierced with a 45 double elliptical slot, 1, in which is placed a cam, 2, of similar contour but of less dimension, so as to be allowed to move freely back and forth in said slot. The periphery of the slot in the cross-head serves as a guide for the 50 crank-pin *a* on one side, and the cam serves as a guide upon the opposite side of said crank-

pin. Cam 2 is made to vibrate back and forth in the slot to allow the crank-pin *a* to pass around the same as it is driven by the cross-head. To accomplish this movement and to 55 hold and support the cam in its proper relative plane, I provide the following device:

3 represents a U-shaped yoke, which is securely bolted at either end to the cross-head F, as shown in Figs. 5 and 8. 4 represents a stud-pin projecting down from said yoke. 5 represents an oscillating arm which is journaled upon said stud 4.

6 represents a stud projecting through arm 5 and engaging with a guide-piece, 7. This 65 guide is rigidly and securely attached to the cam 2, as shown in Figs. 4 and 7.

In order to move the cam from side to side alternately of the slot 1, I have provided the 70 following instrumentalities:

8 represents a support, preferably arched or bent, and secured to the frame-piece A B, lying longitudinally outside of the plane of the moving parts. 9 represents an arm projecting from said support laterally. 10 represents 75 a stud-pin projecting inward from said arm. As the cross-head F is reciprocated past the point of said stud, the end of arm 5 engages therewith, turns upon its center, and moves the cam 2 within the cam-slot 1, changing its 80 position from one side of the slot to the other, as illustrated by the dotted lines, Fig. 5, and when the arm is in the position shown in said dotted lines the reverse movement of the cross-head F changes it back to the position 85 shown in Fig. 1. Thus the stud 10 and the arm 5 serve as puppets to move the cam 2. This movement occurs when the crank-pin is in either of the positions shown in dotted lines *a*, Fig. 5, which movement takes place at the 90 center line during the movement of the cross-head or stroke of the piston-rod.

c represents guides, and *d* represents slots in the cross-piece 7, fitting over said guides, so as to preserve the parallel movement of the 95 cam.

When the crank-pin arrives at its position shown in Fig. 2—that is, to the central point of the cam and elliptical slot—it would be liable to reverse its movement and go backward 100 instead of forward, in the direction indicated by the arrow, when it is on the central point

at either side of the cam. To prevent this and to secure a continuous forward movement, I have provided central guide-pins, 11 12, which are made to reciprocate and come down 5 behind the crank-pin *a*, one of which movements is illustrated in Fig. 3, showing the central guide 12 with its bevel-face behind the crank-pin *a*, which prevents its moving backward when the opposite central guide, 11, 10 is retracted. These guides 11 12 are constructed and reciprocated in the following manner: The cross-head F is bored out to receive these guides, which reciprocate longitudinally in said bores, as shown in Fig. 3. 15 13 represents the cylindrical portion of these guides. 14 represents a gear, which is keyed in said guide-pins for the purpose of allowing them to be rotated half round to reverse the crank movement of the engine. These guides 20 are reciprocated by means of compound link movements, 15 representing a link-arm pivoted at one end to the cross-head by stud 16 and at the other end to a second link, 17. To the opposite end of link 17 is pivoted a link, 25 18, the inner end of which engages in the annular slot 19, chased around the guides 11 12, as shown in Fig. 3. These links are operated by means of studs 20 21, placed at either end of the frame A B. The stud 21, striking the 30 link 15, moves the links 17 18, which move the guide 12 inward in the position shown in Fig. 3, and the stud 20 moves the opposite links, 15 17 18, to move the center guide 11 inward. 35 In order to retract the guides 11 12, I have provided a guide, 22, which is supported in proper position, so that its ends will engage with the link-arms 15, to move them outward and retract the center guides, 11 12, alternately 40 upon either side of the stroke. In order to reverse the movement of the crank, it is necessary that the center guides, 11 12, should be turned around one-half of a revolution, so as to come upon the opposite side of the crank- 45 pin, to compel the crank to turn around in the opposite direction from that indicated by the arrows. This I accomplish preferably by the following instrumentalities:

23 represents a crank-arm journaled upon 50 the frame A B.

24 25 represent segmental gears rigidly secured to a movable collar, 26, which is journaled so as to reciprocate longitudinally upon said crank-rod. This crank-rod is preferably 55 many-sided, and the collar 26 provided with a similar-shaped opening, so as to reciprocate upon said crank-rod, and yet allow it to be turned to move the segmental gears which engage with the gears 14, cut upon the center 60 guides, 11 12.

27 represents a crank-arm rigidly secured to the crank-rod 23.

28 represents a segment; 29, a latch which engages in notches 30 31, so as to hold the 65 crank-arm rigidly in either position.

The movement of the crank-arm from notch 30 to 31 turns the segments 24 25 a sufficient

distance to revolve the gears 14 one-half a revolution, reversing the faces of the points of the center guides, 11 12. Piston-rod E is shown 70 as journaled in the frame-piece A, and it is connected rigidly to the cross-head F by means of the yoke 32.

The operation of my device is as follows: The piston-rod E is reciprocated by means of 75 steam or other motive agency reciprocating the cross-head, which is guided upon the side frame-pieces, C D. The periphery of the elliptical slot 1, formed in the cross-head, forces the crank-pin *a* and the crank-arm G forward 80 in the plane of its revolution, the crank G being keyed upon the main driving-shaft H to perform the work. When the crank-pin *a* arrives at the extreme outward limit of the slot 1 and beyond the point of the cam at the 85 position shown in dotted lines, Fig. 5, the cam is moved to the opposite side of the slot 1 by means of the stud 10 and arm 5, as before explained, which compels the crank-pin *a* to move forward upon the opposite side of 90 said cam in the way provided for it by reversing the position of the cam in the cross-head. As soon as the crank-pin *a* has come to the central line of the cross-head and piston, the center guide, 11 or 12, is brought forward by the means before described, so that 95 its bevel face will come in behind the crank-pin and compel it to travel forward to the opposite extreme outward movement of the crank-pin in its position in the cross-head, when the cam is reversed by the instrumentality above described moving forward upon the opposite side of said cam. This reversal of the cam takes place when the cross-head F is at the 100 central point of its lateral movement, and the 105 inward movement of the guide 12 takes place when the cross-head F arrives at its extreme lateral movement toward the frame-piece B, and the guide is retracted when it commences to recede or move in the opposite direction. 110 The center guide 11 is operated in like manner when the cross-head F is making the opposite end movement. Thus I am enabled, by means of the reciprocating cross-head F, to drive the crank by means of the cam, and the 115 leverage power of the cam upon the crank-pin and crank-arm is very nearly equal through all portions of its path.

I claim—

1. The cross-head F, provided with the 120 double elliptical slot 1, in combination with the double elliptical and intermittent reciprocating cam 2, substantially as specified.

2. In combination with a crank-pin, the cross-head F, having a double elliptical slot, 125 1, and the double elliptical cam 2, supported within said slot and provided with shifting puppet devices for automatically moving said cam from one side of said slot to the other at the central line of movement, substantially as 130 described.

3. In combination with a cross-head frame, the cross-head F, provided with the double elliptical slot 1, the double elliptical cam 2, the

puppet shifting devices attached to said cam, the crank G and crank-pin *a*, and the piston-rod E, attached to said cross-head, substantially as specified.

5 4. The combination, with a crank-pin and the cross-head F, provided with a double elliptical slot, 1, of the double elliptical cam 2, located therein, shifting puppet devices for automatically moving the cam from one side of 10 the slot to the other, and intermittently-reciprocating center guides, 11 and 12, substantially as described.

5 5. The combination, with a crank-pin and the cross-head F, provided with the cam-slot 15 1, of the shifting-cam 2, located therein, and

the longitudinally-reciprocating center guides, 11 and 12, substantially as described.

6. In combination with the crank - pin *a*, slotted cross-head F, cam 2, and central guides, 11 12, provided with bevel faces, the adjusting mechanism, substantially as described, for moving said guides half round to change the stroke, substantially as specified. 20

In testimony whereof I have hereunto set my hand.

DAVID P. WHITESELL.
